UNITED STATES PATENT OFFICE.

DELL S. CROSBY AND JULIUS R. MEYERS, OF CHICAGO, ILLINOIS.

DESIGN FOR A FOLLOWER FOR CHEESE-MOLDS.

SPECIFICATION forming part of Design No. 34,242, dated March 19, 1901.

Application filed February 20, 1901. Serial No. 48,192. Term of patent 7 years.

To all whom it may concern:

Be it known that we, DELL S. CROSBY and JULIUS R. MEYERS, citizens of the United States, residing at Chicago, in the county of Cook and State of Illinois, have invented and produced a new and original Design for a Follower for Cheese-Molds, of which the following is a specification, reference being had to the accompanying drawing, forming part hereof.

Said drawing is a perspective view of a follower made in accordance with our novel design.

The leading or characteristic features of a follower for cheese-molds made in accordance with our novel design are as follows: The follower has the form of a flat rectangular board or plate and is made of somewhat greater length than width. On one face of the follower are located a plurality of parallel uniformly-spaced transverse ridges which extend at their ends nearly to the side margins of the follower and project a distance beyond the surface of said follower. The end ridges of the series are each located a distance from the adjacent end of the follower slightly greater than the distance between adjacent ridges. Surrounding the part of the face of the follower on which are located the said ridges is a strip having a rounded outer edge which is substantially flush with the side and end margins of the follower, the outer surface of the body of said strip being substantially flush with the surface of the follower.

What we claim as new is—

The design for a follower for cheese-molds substantially as herein shown and described.

Signed at Chicago, Illinois, this 13th day of February, A. D. 1901.

DELL S. CROSBY.
JULIUS R. MEYERS.
